RADIATOR

Walter E. Kuenstler, Grantwood, N. J.

Application August 15, 1934, Serial No. 739,847

4 Claims. (Cl. 237—73)

This invention relates to an improvement in radiators for heating purposes and has for its object to provide a radiator structure more particularly adapted for single-pipe heating systems and having improved heating efficiency and operation.

It has been determined that a great deal of the inefficiency in heating, and the noises occurring in single pipe heating systems, is due to the manner in which the steam is directed into the radiators and the course which the steam follows therein. In a radiator of conventional construction the steam enters the radiator at one end of the same, flowing in a horizontal direction, and upon entering the bottom passage of the radiator, it rises in the various sections of the radiator. The condensation water, dropping down in the various radiator sections, flows back along the lower horizontal passage where the steam is entering and against the velocity of the steam. During the heating up of the radiator, this causes water hammer. Water hammer or radiator "knocking" so common in single pipe radiator systems, is caused by water attempting to flow along a slightly inclined or horizontal plane against the velocity of steam flowing in an opposite direction. The velocity of the steam drives the water against the end of the passage with such force as to create hammer. It is obvious from this, that a radiator so designed as to provide a passage wherein steam is injected and in which water will collect and flow, is one wherein hammer and knock is most likely to occur.

The primary object of my invention, therefore, is to provide a radiator so designed that the steam upon entering the radiator, is directed upwardly or vertically toward the top of the radiator and is distributed through the top passage thereof, permitting the condensation and steam to descend together in the same direction. With this arrangement, the venting air, steam and condensation do not meet in an opposing flow until the condensation reaches the steam inlet opening and then it meets the steam only in a vertical flowing position so that water hammer does not occur.

A further feature of the invention resides in the venting of air at the bottom of the radiator. By directing the steam to the top of the radiator, it flows downwardly and forces the air before it in its natural flow. In this manner, the air, steam and water all flow in the same direction and water hammer and air binding is completely avoided.

In the accompanying drawing, wherein an em-

bodiment of the invention is shown, Fig. 1 is a front elevation, with parts in section of the improved radiator; Fig. 2 is a sectional view on the line 2—2 of Fig. 1, looking in the direction of the arrows; and Fig. 3 is a sectional view on the line 3—3 of Fig. 1, looking in the direction of the arrows.

In the drawing, 5 and 6 indicate the end sections of the radiator. Each of said sections is provided with supporting legs 8, upon which the radiator is held in an elevated position above the floor. The end sections are each provided with a closed, relatively flat end wall 7 spaced from an inner wall 9 to provide a vertically disposed fluid passage 10 between them. The passage 10 communicates at its lower end with a boss 11 and at its upper end with a boss 12, these two bosses connecting respectively with the bosses 13 and 14 formed on the adjacent intermediate section 15 of the radiator. The intermediate section 15 of the radiator is provided with the bosses 13 and 14 connected by the nipples 22 with the bosses 11 and 12 on the end section 5.

The intermediate section 15 is provided with a vertically extending, flat fluid passage 16 which communicates with the bosses 13 at its upper end and with the bosses 14 at its lower end. At its lower end, the passage 16 is formed with an enlarged outlet 17 which connects to the steam inlet pipe 18 in which a shut-off valve 19 is located. It will thus be seen that steam entering into the radiator from the pipe 18 will be directed vertically up through the passage 16. Connected to the intermediate radiator section 15 is a plurality of additional intermediate sections 20 which are similar in construction and shape to the intermediate section 15 except that the lower ends of the passages 16 are closed, as shown at 21 in Fig. 1.

The intermediate sections 20 are provided with the bosses 13 and 14 which connect together by means of the nipples 22 so that the radiator is provided with the continuous, horizontally disposed fluid passages 23 and 24 communicating with the vertical fluid passages 10 and 16 in the radiator sections.

The intermediate sections 15 and 20 of the radiator are provided at their front and rear with laterally extending flanges 25, the longitudinal edges of which abut when the sections are placed together so that the radiator presents a relative smooth flat face on its front and rear. The several sections are also provided at their top with flanges 26 so that the top also of the radiator is provided with a continuous smooth upper face. 55

At the upper portion of the front, and if desirable at the rear or top, the flanges 25 on the several radiator sections are recessed as at 27 in Fig. 1 to provide spaced, abutting lugs 28 which co-operate to form a grille between them. The flanges 25 and 26, and the end walls 7 all co-operate in the formation of a radiator in which the front, back, top and ends are in the form of substantially flat or plane surfaces. These flanges and end walls also co-operate to form the vertical flues or air passages clearly shown at 35 in Figs. 2 and 3. As will be there seen, said air passages are located between the several radiator sections, and air entering through the open bottoms of these passages and flowing upward through the same, will be heated by contact with the walls of the steam passages 16 and emerge from the grille openings 27 at the upper front, top or back of the radiator wherever the grille or grilles are located. To aid in heating the air passing through the passages 35, heat-radiating fins 36 are formed on the walls of the steam passages 16, said fins projecting toward one another in the air passage but not in actual contact.

The intermediate section 29 of the radiator located at the right in Fig. 1 is similar in construction to the section shown at 15 and similar reference numerals have been applied to its parts. The widened opening 17, in the section 29, receives an air valve 30 which is threaded vertically into the opening 17.

From the construction described, it will be seen that steam directed through the pipe 18 will be introduced into the radiator in a vertical direction and will reach the top horizontal passage 23 wherein it will be distributed. The condensation and steam will thus flow down together through the several vertical passages 16 to reach the lower horizontal passage 24. With this arrangement, the steam, condensation, and venting air are all moving in the same direction so that water hammer and noises incidental to the conventional single section type of steam system will be completely avoided.

What I claim is:

1. In a radiator, end sections, a plurality of intermediate sections disposed between and connected to the end sections, an intermediate section situated contiguous to one of the end sections having a heating-fluid inlet opening located at its bottom, an air valve chamber located in the bottom of an intermediate section situated contiguous to the other end section, there being a plurality of intermediate heating sections located between and separating those sections in which the fluid inlet opening and valve chamber are respectively located, the inlet opening being situated in its section at a point located substantially on the vertical center line of said section, the air

valve chamber being also located on the vertical center line of its section whereby a substantially equal amount of heating surface is disposed on opposite sides of the vertical center lines of said chamber and opening transversely of the length 5 of the radiator in each of the sections in which the opening and chamber are respectively located.

2. In a radiator adapted for single pipe heating systems, end sections, a plurality of intermediate 10 sections disposed between and connected to the end sections, the various connected sections having upper and lower horizontally disposed fluid passages connected by vertically disposed passages, one of the vertically disposed passages being located in an intermediate section situated contiguous to and connected to an end section, having its lower end enlarged to form a vertically disposed inlet opening whereby steam passing therethrough will be injected directly upward 20 through the vertically disposed passage and toward the upper horizontal passage, and an air vent valve located at the enlarged lower end of an intermediate section situated farthest from the section in which the inlet opening is located, said 25 valve being disposed within the section in which it is located.

3. In a single pipe system radiator, a plurality of connected sections containing vertical fluid 30 passages connected to upper and lower horizontally disposed fluid passages, one of the vertically disposed passages located contiguous to one end of the horizontal passages having a widened downwardly directed opening for connection to an inlet pipe, said opening being located on the vertical center of the passage, another of the vertically disposed passages located adjacent to the opposite end of the horizontal passages provided with a widened centrally located downwardly directed opening, and a closure member for the last 40 mentioned opening constructed to retain an air vent valve within the last mentioned widened vertically disposed passage.

4. In a single pipe system radiator, a plurality of connected radiator sections co-operating to 45 form an upper horizontally extending fluid passage and a lower horizontally extending fluid passage, each of said sections having a vertical passage extending between and communicating with the two horizontal passages, one of the sections at one end of the radiator having the lower 50 end of its vertical passage enlarged at a central point to form a central connection at the bottom of the section for a heating fluid inlet pipe, another section at the opposite end of the radiator 55 having a similar enlarged central portion at its lower end forming a chamber for the reception of a valve.
